SHELF, HOLDER, AND THE LIKE

Victor M. Opper, New York, N. Y.

Application October 31, 1939, Serial No. 302,213

1 Claim. (Cl. 211—60)

This invention relates generally to improvements in devices for supporting articles and more particularly to an auxiliary or depending shelf from which may be suspended, certain toilet articles and the like.

It is an object of the present invention to provide in combination with a cabinet shelf, an auxiliary or depending shelf supported by the cabinet shelf and having means whereby tubular containers holding toilet articles, medicaments and the like may be suspended therefrom. In toilet cabinets of the present type no provision is made for the convenient and orderly arranging of such articles and others such as razors and other implements, with the result that these articles often are not readily accessible for use when desired and the cabinet or shelf presents an unsightly appearance.

A further object of the present invention is to provide an auxiliary shelf having practical means for supporting the same from another shelf and a slotted portion adapted to receive articles to be suspended therefrom, the slotted portion being raised at an angle in order that the articles may be held securely in suspended position.

It is a further object of the present invention to provide the rear portion of the slots with converging walls to facilitate wedging of the articles thus suspended.

These and other objects of the invention and the means for their attainment will be more apparent from the following detailed description, taken in connection with the accompanying drawing, illustrating certain embodiments of which the invention may be realized, and in which:

Fig. 1 is a perspective view of a toilet wall-cabinet having incorporated therein features of the invention;

Fig. 2 is a sectional view taken along line 2—2 of Fig. 1 and looking in the direction of the arrows.

Fig. 3 is a top plan view of an auxiliary or depending shelf or support embodying the invention;

Fig. 4 is a front elevational view of the auxiliary shelf shown in Fig. 3;

Fig. 5 is a detail sectional view taken along line 5—5 of Fig. 4, looking in the direction of the arrows;

Fig. 6 is a view of part of the device illustrated in Figs. 1—5, showing an alternative means of attaching the device to a toilet cabinet.

Fig. 7 shows a means for supporting the auxiliary shelf from the cabinet shelf; and

Fig. 8 shows an auxiliary or depending wire structure embodying the invention in a modified form.

Referring to the drawing Figs. 1 and 2 show the invention applied to a wall-cabinet 10, the latter being set into a recess in the wall 11. Cabinet 10 may have the conventional shelves 12 maintained in spaced relation by means of the pegs or pins 13 inserted in the holes 14 of the side walls 15 of the cabinet. The cabinet may be provided with a swinging door 16.

Referring now to the auxiliary or depending or supplementary shelf indicated generally by the numeral 17, the same may comprise a strip of metal of the non-corrosive type or made non-corrosive by applying thereto a suitable coating, bent or shaped to form a horizontal upper ledge 18, a vertical rear wall 19 and a longitudinal lower member 20. The parts 18 and 19 are at a right angle to each other, whereas, the member or part 20 is preferably slanted upward from vertical wall 19 at approximately fifteen degrees with respect to an imaginary horizontal line.

Member 20 is provided with a plurality of slots 21, 22 adapted to receive the head or top portions of articles to be suspended from the device 17. The walls of the slots are preferably made straight or parallel in front and tapering or converging in the rear as indicated by the numerals 23, 24, respectively. Since the member 20 is tipped at an angle with its outermost edge upward when the necks of articles such as the tubes 25, 26 (Fig. 1) are inserted in the cut-outs or slots 21, the same will slide towards the rear of the device and become wedged between the tapered walls 24, and thereby will be securely maintained in position.

These supporting slots are preferably made in different widths, such as, illustrated at 21 and 22 to accommodate various sized necks of articles to be suspended. The slots may be variously spaced from each other to allow for the differences in widths and thicknesses of the articles to be suspended as shown at 27 and 28.

In the embodiment illustrated in Figs. 1—5, inclusive, the auxiliary shelf is suspended by the ledge 18 resting on the top surface of the cabinet shelf 12', at the rear thereof, the wall 19 thereof being disposed between the rear wall 30 of the cabinet and the rear edge 31 of the shelf 12'.

Fig. 6 shows the left hand portion of the supplementary shelf 17 having a notch 32 in engagement with a screw or bolt 33 secured in a wall 34. The right hand portion is provided with a similar notch (not shown).

Fig. 7 is a view of a device incorporating the invention in a modified form and in which the left hand portion of the supplementary or auxiliary shelf is shown.

As illustrated, the device comprises the inclined supporting shelf 20, the rear vertical wall 19' from which extend at each end a clamping member 35 having its lower connecting member 36 projecting from the rear wall 19' at 37 and forming a U-bend 38 in front of shelf 12 and running rearwardly thereby providing a clamping finger 39. Shelf 12 may be suspended within the wall-cabinet or by conventional brackets secured to a wall of a room.

The device 17 may be employed as a separate shelf by attaching the same to a wall or other support.

Fig. 8 shows the invention in a form similar to that shown in Fig. 7, except that the device is formed and bent out of wire, thus providing the slots 45, upright end members 46 and clamping fingers 47.

It is understood that the shelf 17 may be made of any suitable material such as metal, or plastic composition, and that the same may be made entirely of wire or a combination of such materials.

Although the drawing and the above specification discloses the best modes in which I have contemplated embodying my invention, I desire in no way to be limited to the details of such dis-

closure, for in the further practical application of my invention many changes in the forms and proportions may be made as circumstances require or experience suggests without departing from the spirit of the invention within the scope of the appended claim.

Having thus described my invention what I claim as new and desire to secure by Letters Patent is:

In combination with a cabinet having a rear wall and a horizontal shelf, of a supplementary shelf being U-shaped in cross-section, one leg of the U resting on the upper surface of said cabinet shelf, the base of the U extending downwardly between the rear edge of said cabinet shelf and said cabinet rear wall, and the other leg of the U extending outwardly from the said base and spaced by said base appreciably from the underside of said cabinet shelf, said other leg having a plurality of slots for receiving the neck portions of tubular containers, said slots extending from the outer edge of said leg inwardly to a position closely adjacent the said base of the U whereby the said tubular containers may be supported by said other leg without appreciable strain thereon, the appreciable spacing of said other leg from the underside of said cabinet shelf affording a substantial bearing of said base against said rear wall of the cabinet.

VICTOR M. OPPER.
